UNITED STATES PATENT OFFICE.

WILBUR L. SHEPARD AND ERASTUS W. WHITLOCK, OF ELMWOOD,
CONNECTICUT.

WATER HEATER AND PURIFIER.

SPECIFICATION forming part of Letters Patent No. 591,505, dated October 12, 1897.

Application filed December 18, 1893. Serial No. 493,567. (No model.)

To all whom it may concern:

Be it known that we, WILBUR L. SHEPARD and ERASTUS W. WHITLOCK, of Elmwood, in the county of Hartford and State of Connecticut, have invented certain new and useful improvements in Water Heaters and Purifiers, of which the following is a full, clear, and exact description, whereby any one skilled in the art can make and use the same.

10 The object of our invention is to provide an apparatus that may be used for heating water for any purpose and one that shall be accessible and readily cleaned as to the interior.

15 The apparatus is particularly applicable for use as a boiler feed-water heater and purifier, although applicable for heating water for any ordinary mercantile use.

20 To this end our invention consists in the details of the several parts making up the apparatus as a whole and in the combination of such parts, as hereinafter described, and more particularly pointed out in the claims.

25 Referring to the drawings, Figure 1 is a detail view, in central section, of the feed-water heater shown as connected to an exhaust-steam pipe. Fig. 2 is a detail plan view of the same with the upper chamber removed.

In the accompanying drawings the letter *a* denotes the body of the heater, composed 30 usually of a cylindrical shell of wrought or cast metal having at the opposite extremities flanges *a'*, through which bolt-holes may be made for the purpose of securing the end sections to the body part of the heater. This 35 heater-body is usually placed in an upright position and is secured at the lower end to a flange *b'*, formed around the outer edge of a sediment-chamber *b*. This chamber is made with curved or sloping walls, preferably tapered or funnel-shaped, as shown in the drawings, and being made gradually smaller in cross-section from the upper edge toward the center—that is, the lowest point of the chamber. The object of this construction of the 40 sediment-chamber is to cause the sediment and impurities that are precipitated from the water that enters the heater to accumulate near the central point, from which they can be easily removed through the blow-off outlet *c*, that consists of a pipe connected up to

the bottom of the heater and provided with a suitable check-valve *d*.

At the upper end of the body of the heater a cover is provided that is made up of a scum-chamber *e*, the shell forming the chamber 55 having a flange *e'*, through which bolts *f* are passed for the purpose of securing to it the flange *a'* on the body part of the heater. This scum-chamber is made, preferably, in the form of a conical frustum, as shown, but in any 60 event is made smaller in area near the blow-off outlet *e* than near the edge secured to the body of the heater. The object of this chamber is to provide a space in which the lighter impurities found in water (such as magnesium) 65 may accumulate in a convenient position to be readily blown off.

To the outlet *e* a suitable blow-off pipe *g* is connected and is provided with any suitable valve to control the discharge. This 70 discharge-valve in the outlet-pipe may be in the form of a safety-valve *h*.

Through the walls of the body part of the heater and preferably near the lower end a water-inlet pipe *i* is provided for the discharge 75 into the heater of water from any suitable source of supply either from the boiler feed-pump or from any other source under pressure.

Near the upper end of the heater, but at a 80 point from which comparatively pure water may be drawn, an outlet-pipe *j* is connected, and through this latter pipe the heated water passes to any desired point.

The water being supplied to the heater under pressure it is obvious that some means must be provided for controlling the discharge of water therefrom to provide its delivery in suitable quantities, and this means may consist of any well-known device. 85

In case the apparatus is used for heating boiler feed-water the discharge, of course, is made directly into the boiler.

Arranged within the heater there is one or more coils of pipe *k*, each coil being connected 95 with a source of steam-supply at one or both ends of the coil.

In the form of apparatus shown an exhaust-steam pipe *m* is connected up to the lower end of the coil and also to the upper end by 100

the branches l' l'' . Each of these branches is provided with a suitable form of cock or valve to enable the apparatus to be at any time cut off from the source of steam-supply.

5 The operation of the device is as follows: The water being supplied to the heater under pressure, as described, the heater is full to the apex of the cone e at all times when the device is in operation. The heavier impurities in the water settle to the bottom of the cone-shaped sediment-chamber b , where they are drawn off, as described. The lighter impurities accumulate at the top of the cone e in form of a scum and the full pressure of 15 water being turned on, or the pump started to cause a pressure of the water within the heater, the valve in the pipe g is open and the impurities blown off therethrough. This valve is in the form of a safety-valve, as 20 shown, so that should the discharge of water through the pipe j be stopped and a pump or like device supplying water continue its operation any danger of bursting the heater by overpressure will be avoided.

25 We claim as our invention—

1. In combination in a water-heater, the shell, a cone-shaped cap secured to and with its axis in line with the axis of the shell and

forming a tapered scum-chamber, a coil of pipes arranged within the shell, and a blow-off pipe extending through the wall of the tapered cap at the highest part of the chamber, and with its axis in line with the axis of the cap and shell, all substantially as described.

2. In combination in a water-heater, a shell, a cone-shaped cap secured to and with its axis in line with the axis of the shell and forming a tapered chamber, a coil of pipes arranged within the shell, a blow-off pipe extending through the wall of the tapered cap at the highest part of the chamber and with its axis in line with the axis of the cap and shell, and an outlet from the shell located below the line of water-level in the boiler.
